ATTORNEY.

UNITED STATES PATENT OFFICE.

MOSES LALONDE, OF SPRINGFIELD, MASSACHUSETTS, ASSIGNOR OF ONE-HALF TO
LOUISE LALONDE, OF SPRINGFIELD, MASSACHUSETTS.

TOY.

1,337,661.

Specification of Letters Patent. Patented Apr. 20, 1920.

Application filed December 8, 1919. Serial No. 343,144.

To all whom it may concern:

Be it known that I, MOSES LALONDE, a subject of the King of England, residing at Springfield, in the county of Hampden and 5 State of Massachusetts, have invented a new and useful Toy, of which the following is a specification.

My invention relates to improvements in toys of the flying and spinning type, and 10 consists essentially of a longitudinally bored handle, a spinning member or top having a stem for an actuating or spinning cord, which stem with the cord thereon is receivable in said handle, and an aerial mem- 15 ber or flier that is attachable to and detachable from the spinning members, all as hereinafter set forth.

The primary object of my invention is to produce a toy of the class described, which 20 is in the nature of a combined toy, that is to say, one that may be used either as a flier or as a top, the same being simple in construction and operation, inexpensive to manufacture, and well adapted to afford a large 25 amount of amusement to children.

Another object is to provide such a toy with simple means whereby the spinning and whirling or flying members can be easily and quickly separated and reunited.

30 Other objects and advantages will appear in the course of the following description.

I attain the objects and secure the advantages of my invention by the means illustrated in the accompanying drawings, in 35 which—

Figure 1 is a side elevation of a toy which embodies a practical form of my invention, all of the parts being united and ready for use; Fig. 2, a central, vertical section 40 through said toy, the handle being at right-angles, relative to the flier, to the position which said handle occupies in the first view; Fig. 3, an enlarged, top plan of the handle; Fig. 4, an enlarged, bottom plan of the top, 45 and, Fig. 5, an enlarged, bottom plan of the flier.

Similar reference numerals designate similar parts throughout the several views.

The toy comprises a handle 1, a top con- 50 sisting of a head 2 and a shank or spindle 3,

and a flier 4. With these parts and members a string or cord 5 is employed.

The handle 1, which is round in cross section, has a central, longitudinal passage 6 extending through the same from end to end, 55 and also has oppositely-disposed, longitudinally-extended slots 7—7 in the upper end or head thereof. The slots 7 open at their upper ends through the top of the handle 1. The diameter of the passage 6 is large 60 enough to receive the spindle 3 with the cord 5 when wound on said spindle, and to permit said cord to be drawn off freely from the spindle.

The lower terminal of the spindle 3 is 65 tapered to form the point of the top and afford a good anchorage for the cord 5. The head 2 is a disk of larger diameter than that of the handle 1, and said head is fixedly attached to the spindle 3 at the upper end 70 thereof. A pair of L-shaped hooks 8 is set in the under side of the head 2. These hooks are oppositely disposed to each other, and arranged with the free ends of their horizontal parts or heads directed toward a 75 plane which extends through the axial center of the head 2 and between such ends.

The flier 4, as herein shown, has two propeller blades 9 which project from opposite ends of the central portion of the flier, such 80 blades being shaped in the usual manner to enable them to carry said flier upwardly in the air, when the flier has the necessary impetus imparted thereto. There is a central opening 10 in the flier 4 to receive the spindle 3. The central portion of the flier 4 is beveled on the bottom adjacent to the longitudinal edges of such portion, as represented at 11—11. The flier 4 is attached to the head 2 of the top by passing the spindle 90 3 down through the opening 10 in said flier, locating the latter between the hooks 8, and partially rotating the same in the direction to introduce the beveled edges 11 beneath the heads of said hooks and thus wedge the 95 flier between the under side of said head 2 and the heads of the hooks. The heads of the hooks 8 are located just the right distance from the head 2 to enable the beveled edges 11 to be forced into the spaces between 100

said head 2 and said heads of the hooks with a binding fit. In this manner and by this means the flier is attached to the top with a sufficient degree of security. The 5 flier is disengaged from the hooks and disconnected from the top by reversing the aforesaid operation, said flier first being partially rotated in such a manner as to carry it out of engagement with said hooks 10 and clear of them, and then slipped off of the spindle 3.

When the device is to be used as an aerial toy the flier 4 must be united with the head 2, in the manner set forth above, but when 15 said device is to be used as a top said flier is disunited and removed from said top, also in the manner set forth above. In either of these cases the required initial motion is imparted to the whirling or spinning element by 20 means of the cord 5. Said cord is first wound on the spindle 3, beginning at the tapered base and continuing upwardly nearly to the top of said spindle, next the spindle with the cord wound thereon is introduced into the 25 top of the handle 1 and inserted therein as far as the flier 4 or the head 2, as the case may be, permits, such flier or head coming to rest on the upper edge of said handle, and finally said cord is drawn with a quick motion 30 from the spindle. Care is taken when placing the spindle 3 in the handle 1 to locate the free portion of the cord which is left after winding, or that part of the same that is immediately adjacent to said spindle, 35 in one or the other of the slots 7, so that said cord can be drawn off of the spindle 3 freely or without undue frictional resistance, so far as said handle and the member resting thereon are concerned. The cord is of such 40 length that there is a sufficient portion outside of the handle, after said cord has been wound on the spindle 3 and the latter inserted in the handle, to enable the operator to obtain a firm hold thereon for the purpose 45 of drawing it off of said spindle. The cord 5, when drawn off of the spindle 3 through one of the slots 7, not only imparts a rapid rotation to said spindle and attached parts, but at the same time elevates the same, with 50 the result that the spindle is caused to leave the handle at the end of what may be termed the starting operation, which is at the instant the cord is entirely freed from the spindle. Thus it is seen that the spindle 55 with attached parts is sent whirling upward from the handle by the action of the cord.

If it be desired to spin the top, the flier 4 is laid aside, and the spindle 3 with its head 2 only is employed. When these parts are 60 set in motion by the cord 5 and the spindle 3 has left the handle 1, all as hereinbefore explained, said top quickly descends to the ground and spins thereon on the point of said spindle, similarly to any ordinary top.

On the other hand, if it be desired to whirl 65 the flier 4, the latter is fastened in place under the head 2. When these parts are set in motion by the cord 5 and the spindle 3 leaves the handle 1, in the same manner as before, said flier with attached parts in motion ascends to a considerable height and continues for some little period of time, or until the whirling motion becomes sufficiently slow to cause the aerial members to fall. The flier and attached parts do not 75 spin on the ground.

The above described operations may be repeated indefinitely.

More or less change in the size, shape, construction, and arrangement of some or 80 all of the parts of this toy may be made without departing from the spirit of my invention or exceeding the scope of what is claimed.

What I claim as my invention, and desire 85 to secure by Letters Patent, is—

1. The combination, in a toy, with a handle having a longitudinal passage through the same and a lateral aperture, of a top comprising a head and spindle, said spindle 90 being adapted to have a cord wound thereon, said passage being of a size to receive freely said spindle with the cord wound thereon, and the aperture being designed to permit the free terminal portion of such cord to 95 pass to the outside of said handle, and a flier attachable to and detachable from the under side of said top, and perforated to receive said spindle.

2. The combination, in a toy, with a handle having a longitudinal passage through the same, and a lateral aperture, of a top comprising a head and spindle, the latter being adapted to have a cord wound thereon, said passage being of a size to receive freely 100 said spindle with the cord wound thereon, and the aperture being designed to permit the free terminal portion of such cord to pass to the outside of said handle, and a flier, said head being provided on the under 105 side with engaging and releasing means for said flier, and the latter being perforated to receive said spindle.

3. The combination, in a toy, with a handle having a longitudinal passage through the same and a lateral aperture, of a top comprising a head and spindle, which head is provided on the under side with hooks, said spindle being adapted to have a cord wound thereon, said passage being of a size 115 to receive freely said spindle with the cord wound thereon, and the aperture being designed to permit the free terminal portion of such cord to pass to the outside of said handle, and a flier adapted to be engaged by 120 and released from said hooks.

4. The combination, in a toy, with a handle having a longitudinal passage there-

through, and a lateral aperture therein, of a top comprising a head and spindle, which head is provided on the under side with hooks, said spindle being adapted to have a 5 cord wound thereon, said passage being of a size to receive freely said spindle with the cord wound thereon, and the aperture being designed to permit the free terminal portion

of such cord to pass to the outside of said handle, and a flier having beveled edges for 10 engagement with said hooks.
